HIGHWAY MARKER

Baxter B. Sapp, Raleigh, N. C.

Application August 28, 1933, Serial No. 687,220

13 Claims. (Cl. 91—18)

The present invention relates to improvements in highway markers, and more especially to machines to marking traffic guiding lines on highways as the machine travels thereon.

One of the primary objects of the invention is to provide a novel and improved machine of this class which comprises a vehicle adapted to travel along the highway and a painting machine connected thereto to travel therewith and carrying means for painting a traffic guiding line on the pavement or surface of the highway as the vehicle advances, means being provided for steering or setting the course of the painting machine relatively to that of the vehicle to conform with curves of different radii in the highway and to thereby enable the traffic guiding line to be applied to the center of the width of the highway at curves therein as well as along straight portions thereof.

Another object is to provide a sanding device cooperative with the painting machine for applying sand to the painted traffic guiding line immediately after the painting thereof, thereby covering the same and thus preventing picking up of paint therefrom and spreading thereof upon other portions of the pavement or surface of the highway by the wheels of vehicles crossing the traffic guiding line after the same has been painted and before it is dry.

Another object is to provide novel and improved means for applying the paint to the pavement or surface of the highway whereby the traffic guiding line may be made of different widths as desired, the marginal edges of the painted line will be sharply defined, and splashing or dropping of paint beyond the margins of the painted line is prevented.

A further object of the invention is to provide the vehicle to which the painting machine is attached with steering means located to be operated by the attendant while in a position where an edge of the highway is visible so that it may serve as a gauge for the steering of the vehicle in a course along the highway which will insure the painting of the traffic guiding lines in proper position thereon.

To these and other ends, the invention consists in certain improvements and combinations and arrangements of parts all as will be herein-after more fully described, the features of novelty being pointed out particularly in the claims at the end of the specification.

In the accompanying drawings:—

Fig. 1 is a top plan of a highway marker con-

structed in accordance with the present invention;

Fig. 2 is a side elevation of the forward portion of the vehicle as viewed from the right hand side thereof or from the upper side of Fig. 1; 5

Fig. 3 is a side elevation, on an enlarged scale, of the rear portion of the vehicle and the painting machine and sanding device attached thereto, as viewed from the left hand side of the vehicle or the lower side of Fig. 1; 10

Fig. 4 is a horizontal section, on an enlarged scale, taken on the line 4—4 in Fig. 3;

Fig. 5 is a vertical section through the painting machine, taken on the line 5—5 in Fig. 4; 15

Fig. 6 is a vertical section through the painting machine, taken on the line 6—6 in Fig. 4;

Fig. 7 is a top plan view of the sanding device; 20

Fig. 8 is a vertical section through the sanding device, taken on the line 8—8 in Fig. 7;

Fig. 9 is a detail section of a part of the attaching means for the painting machine, on an enlarged scale and taken on the line 9—9 in Fig. 1; 25

Fig. 10 is a vertical section taken on the line 10—10 in Fig. 9; and 25

Fig. 11 is a detail sectional view of the locking dog and segment for controlling the steering of the painting machine.

Similar parts are designated by the same reference characters in the several figures. 30

The preferred embodiment of the invention is shown in the accompanying drawings and will be hereinafter described in detail but it is to be understood that the invention is not restricted to the precise construction shown since equivalent constructions are contemplated and such will be included within the scope of the claims. 35

In the present instance, the invention is shown applied to a highway marker of the same general class as that shown and described in Letters Patent No. 1,763,432, granted June 10, 1930, it however providing improvements thereover, as will hereinafter appear. 40

The improved highway marker comprises generally a vehicle, preferably a motor truck or other appropriate automotive or self-propelled vehicle and a painting machine for painting the traffic guiding lines, the painting machine having means for attaching it to the vehicle so that it will be drawn thereby and will be appropriately guided or steered, and in some instances where such is desired or required, a sanding device is provided to cover the freshly painted traffic guiding line with sand and thereby prevent tracking of paint 45

therefrom onto other portions of the pavement of the highway.

The vehicle shown in the present instance comprises an ordinary motor truck having a frame or chassis 1, front and rear wheels 2 and 3, the front wheels being pivoted to the front axle as usual and provided with steering means controlled by the ordinary steering wheel 3^a, as in an ordinary motor truck. However, for the purposes of the present invention, the motor truck is provided with an auxiliary steering gear 4 for the front wheels 2, this auxiliary steering gear being controlled by an auxiliary steering wheel 5 which is mounted at the right hand side of the truck, an auxiliary seat 6 being provided which an attendant may occupy for manipulation of the auxiliary steering wheel, and the right hand front fender 7 which usually shields the right hand front wheel of the ordinary truck is hinged on a horizontally extending hinge pin 8 toward the inner side of this fender so that the latter may be swung upwardly and inwardly toward or against the hood 9 of the truck and thereby expose the right hand front wheel of the truck and also the right hand edge of the pavement of the highway to the attendant occupying the seat 6 and controlling the auxiliary steering wheel 5 so that this attendant may guide the truck by the auxiliary steering wheel 5 so as to cause the right hand front wheel 2 to travel along the right hand edge of the pavement of the highway and thus utilizing this edge of the highway as a gauge to position the painting machine attached to the left hand side of the truck, as will hereinafter appear, centrally of the width of the highway. A catch 10 may be provided for retaining the hinged fender 7 in its lowered normal position during the travel of the truck when the painting machine is not in operation.

The truck is also provided with a suitable body 11 on which are mounted a suitable number of paint supply tanks, two of these tanks 12 being shown in the present instance, and the truck body also carries a compressed air supply tank 13, the latter being provided with an air compressor 14 for supplying compressed air thereto, this air compressor being preferably driven by an internal combustion engine 15 which is independent of the engine which propels the truck. The truck body is also shown provided with a rotary or other suitable and well known type of pump 16 which may be belted to or otherwise driven from the engine 15, this pump having an inlet 17 adapted to be connected by a hose or otherwise to paint drums or receptacles containing a supply of paint and the pump is connected by a pipe 18 to the paint supply tanks 12 whereby the pump may be used to fill these paint supply tanks on the truck from paint containing drums or other receptacles. The paint supply tanks 12 may be provided with agitating devices therein for maintaining the paint in properly mixed condition, as for example is shown in the above noted patent, and such agitating means may be driven in any suitable manner, as by compressed air motors 19 which may be mounted on the tops of these tanks. The paint, in liquid condition, is conducted from the supply tanks 12 through a flexible hose 20, and compressed air is supplied from the tank 13 through a flexible hose 21.

The painting machine according to the present invention comprises a main frame 22 which is preferably yoke-shaped in form to provide side arms 23 the rear ends of which are bent downwardly to form substantially upright side mem-

bers 24, the side members of the frame being bent toward one another at the front and rigidly secured together by a head 25. The lower portions of the upright frame members 24 have alined axles 26 projecting outwardly therefrom and supporting wheels 27 rotatably mounted thereon, these wheels preferably having pneumatic tires to absorb shocks due to unevenness in the highway surface. Vertical guides 28 are fixed to the inner sides of the upright frame members 24 and 10 slides 29 are individually movable vertically in the respective guides, each of these slides having a shaft 30 rigidly secured thereto near its lower end and projecting inwardly therefrom, these shafts being preferably located in the same vertical plane with the axles 26, and circular paint confining disks 31 are rotatably mounted on the respective shafts. Springs 32, each attached at one end to the respective guide, as by a hook 33, and at its other end to the respective slide, as by 20 an adjustable screw eye 34, serve to individually force the respective disks downwardly relatively to the frame of the painting machine, and thereby maintain said disks in rolling contact with the surface of the highway or pavement, the individual vertical movements provided for these disks enabling them to remain in contact with the highway surface notwithstanding unevenness thereof.

The painting machine frame also comprises a cross member 35 which connects the side arms 23 thereof rigidly and thus maintains them in fixed laterally spaced relation, and the frame also comprises horizontal side members 36 which are rigidly secured to the outer sides of the up-right members 24, these side members being rigidly connected by front and rear cross members 37. The disks 31 are shiftable axially on their respective shafts 30 so that the distance between these disks may be varied to conform with the painting of lines of different widths. The distance between the disks and, accordingly, the width of the line to be painted on the highway, is controlled by suitable means, preferably by rollers 38 carried by posts 39, a pair of these rollers and posts being preferably provided at the outer side of each disk, and the posts are supported adjustably on the respective horizontal side members 36 of the frame by screws 40 which enable the rollers to be adjusted toward and from 50 the respective side members 36, and lock nuts 41 on the respective screws serve to lock the posts 39 and the rollers 38 in different adjusted positions.

Means is provided for removing from the inner sides of the disks surplus paint that may adhere thereto, thereby preventing splashing or dropping of the paint on the highway surface beyond the margins of the line painted thereon. As shown in the present instance, a paint collecting trough 42 is attached by a bolt 43 to a bracket 44 which latter may be attached to the rear cross member 37 of the frame, this trough having a pair of branches 45 which diverge so that they are in contact at their outer edges with the inner surfaces of the respective disks 31, these branches of the trough thus serving to scrape surplus paint from the inner sides of the disks and to cause the paint thus removed to flow by gravity through the trough, and the trough may be provided toward 70 its rear end with a hook 46 upon which a bucket or other suitable receptacle 47 may be hung so that it will receive and collect the surplus paint removed from the disks by the trough. The width of the disk-engaging portion of the trough con-

forms with the spacing apart of the disks, and in order to accommodate different adjustments of the disks for the painting of lines of different widths, a number of troughs may be provided which are of graduated widths to conform with different adjustment of the disks for the painting of lines of different widths. In each instance, the trough interposed between the disks will serve to hold them apart in proper spaced relation.

The painting of the traffic guiding line, which is effected on the portion of the highway surface which extends between the lower edges of the disks, is performed by a paint gun 48 which may be of any suitable or well known construction having valve controlled paint and compressed air supply connections 49 and 50 which are connected to the respective flexible hoses 20 and 21. The paint gun is supported in suitable position between the disks 31 by an arm 51 which is rigidly attached to and extends downwardly from the cross member 35 of the frame. Preferably, the paint gun is so supported that it may be adjusted vertically and thus position its nozzle at the proper elevation above the highway surface to effectively apply and distribute the paint thereon, the paint gun being mounted for this purpose on a slide 52 which is movable substantially vertically on a guide 53 fixed to the supporting arm 51, and a screw 54 to which a handle 55 is attached, serves to adjust the slide 52 and the paint gun connected thereto on the guide 53, the screw in the present instance being threaded in a bracket 56 which supports the guide 53 on the arm 51.

The painting machine is attached to the inner or left hand side of the truck so that it will be drawn thereby, and the attaching means pivotally connects the painting machine to the truck so that the course steered by the painting machine will conform with the course of the truck or vehicle as the latter advances along the highway and especially while the truck or vehicle is traversing a curve in the highway, so that the traffic guiding line will be painted in the center of the width of the highway, on curved as well as upon straight portions thereof, and the attachment between the painting machine and the truck or vehicle includes a universal joint which enables the painting machine, riding on its supporting wheels, to accommodate itself to unevenness or irregularities in the surface of the highway. As shown in the present instance, such attaching means comprises a bracket 57 having arms 58 pivoted at their extremities to square blocks 59 adapted to fit between the out-turned flanges of vertical angle irons 60 bolted or otherwise secured to the inner or left hand side of the frame or chassis of the truck, and bolts 61 serve to secure the blocks 59 between said angle irons and to pivotally connect the blocks 59 to the respective arms 58 of the bracket, the blocks 59 having ledges 59a on which the arms 58 may rest when the bracket is lowered so that the bracket will be supported in its operative position so that it projects substantially horizontally and laterally from the inner or left hand side of the truck. When the painting machine is not in use and the truck is being moved from one place to another, the bracket 57 may be swung upwardly about the pivot bolts 61, into upright folded position against the adjacent side of the truck where it may be held by any suitable means, so that it does not then form an obstructing projection therefrom. The bracket 57 has a bar 62 secured thereto as by clamping screws 63, an end of this bar extending beyond the bracket 75 and having a downwardly offset portion 64. The

painting machine carries a draft bar 65 the forward end of which is provided with means for connecting it to the portion 64 of the bar 62, such connecting means preferably embodying a joint which permits universal movement of the bar 65 and the painting machine relatively to the bar 64, and this connecting means is also adjustable along the bar 64 to vary its distance laterally beyond the side of the truck and thereby provide for the painting of traffic lines centrally between the edges of highways of different widths. Such connecting means as shown comprises a slide 66 which is adjustable longitudinally of the bar 64 and is provided with a set screw 67 for firmly clamping it in different adjusted positions thereon. The slide 66 is formed with a circular hub 68 on which a ring 69 is mounted rotatably so that it may rock or turn on a horizontal axis, and the draft bar 65 is apertured at or near its forward end to rotatably receive a pivot pin 70 which is fixed on a vertical axis in the ring 69, a nut 71 threaded on this pivot pin serving to retain the bar 65 in engagement therewith. The construction just described enables the draft bar 65 for the painting machine to be placed in different positions on the bar 64 and hence spaced at different distances inwardly from the inner or left hand side of the truck, and the rotatable ring 69 and pivot pin 70 enable the draft bar 65 to swing horizontally to conform with different courses steered by the painting machine relatively to the course of the truck and to swing vertically to conform with unevenness in the surface of the highway. The frame 22 of the painting machine is connected to the draft bar 65 by a draw bar 72 which is preferably slidable longitudinally in the head 25 and is provided with a coiled compression spring 73 which bears against the rear side of the head 25 and against a collar 74 fixed on the draw bar so that sudden or uneven pulling of the draw bar 72 will be absorbed or cushioned by the spring 73 and hence jerking of the painting machine from such cause will be avoided. The draw bar 72 is preferably circular in cross section so that it is swivelled or rotatable on a horizontal longitudinal axis in the head 25, such swivelling permitting the painting machine to rock laterally as its supporting wheels at the opposite sides thereof ride over uneven portions of the highway surface. The forward end of the draw bar 72 is operatively connected to the draft bar 65 by a bracket 75 one end of which is pivotally connected to the draft bar so as to rotate relatively thereto, on a vertical axis, by the pivot stud 76 and the other end of said bracket being pivotally connected to the draw bar 72 by a joint having a vertical pivot pin 77.

Means is provided for setting the painting machine in different angular positions relatively to the draw bar 65 so as to cause the painting machine to steer a proper course to apply the traffic guiding line in the center of the width of a curve in the highway, such means comprising a locking segment 78 fixed to posts 79 attached to the rigid cross member 35 of the painting machine frame, and a locking dog 80 which is slidable longitudinally of the draft bar 65 in a guide 81 thereon and having a releasing grip 82 connected thereto by a rod 83, this dog being engageable in one or another of suitably arranged notches 84 formed in the segment 78. Preferably, the notches 84 in said segment are spaced or graduated therein in accordance with the different degrees of curvature of the curves in highways so that by setting the dog in the proper notch in the segment, the painting ma-

chine will be set to steer a course which will insure painting of the traffic guiding line midway of the width of a correspondingly curved portion of a highway. The locking segment 78 is concentric with the vertical pivot 76 which connects the draft bar 65 to the frame of the painting machine, and lateral swing of the draft bar 65 in either direction, and which will shift the pivot 76 in a corresponding lateral direction with respect to the pivot pin 70, will set the painting machine and its supporting wheels 27 which ride upon the surface of the highway in different angular positions relatively to the draft bar 65 and will thereby alter the course steered by the painting machine as the same is drawn forwardly by the pivot pin 70, the rear end of the draft bar 65 being swung toward the truck or vehicle when the curve in the highway to be traversed curves toward the left, and the draft bar being swung away from the truck when the curve in the highway curves toward the right, the supporting wheels 27 of the painting machine being thus directed either toward or away from the truck or vehicle in order to cause the painting machine to traverse a course centrally of the width of the highway when a curve therein is being traversed. The rear end of the draft bar 65 is provided with a handle 85 to facilitate its manipulation to thus control the steering of the painting machine. A seat 86 is provided which may be occupied by an attendant for the painting machine, this seat being supported on a link 87 which is connected by a vertical pivot bearing 88 to a second link 89, and the latter link is connected by a vertical pivot bearing 90 to the rear end of a link 91, the latter being pivoted by a horizontal pivot pin 92 to a bracket 93 fixed to the adjacent side of the truck or vehicle and the latter having a bar 194 fixed at or toward its rear end to underlie the link 91 and thereby provide a support on which it may rest. While the link 91 rests on the bar 194, the links 87 and 89 will be supported to swing in a substantially horizontal plane about the vertical pivots 88 and 90 as centers, thereby enabling the seat 86 to be swung either forwardly or rearwardly or laterally in either direction so that it may occupy the proper position at the rear of the painting machine to enable the attendant occupying the seat to reach and manipulate the painting machine while the vehicle and painting machine are in operation. When the painting machine is not in operation, the link 91 may be swung upwardly about its pivot 92 and the links 87 and 89 and the seat 86 attached thereto may be swung inwardly into or above the truck body so that they do not then form obstructions at the side of the truck.

Preferably, and as shown, the pivot pin 70 from which the painting machine trails, is located at a side of the truck or vehicle in substantial alignment with the axis of the rear wheels 3 thereof, as will be clear from Figs. 1 and 3, with the resulting advantage that the course of the trailing painting machine will be subject to minimum lateral deviation incident to lateral deviations in the course of the truck or vehicle, since the rear wheels of the truck or vehicle are subject to minimum lateral displacement due to lateral deviations or changes in the course of the truck or vehicle in traversing the highway.

In order to compensate for rearward movements of the painting machine permitted by the shock-absorbing or cushioning spring 73 for the draw bar thereof, the locking dog 80 which is engageable with one or another of the notches 84

in the segment 78 carried by the painting machine is slidable in the guide 81 (Fig. 11) fixed to the draw bar 65 and has a stem 84^a connected to the releasing rod 83, a compression spring 84^b encircling the stem and bearing at one end against an adjusting screw 84^c threaded in the guide and at its other end against a lug 84^d on the locking dog, said spring acting to yieldingly force the dog 80 forwardly and thereby hold it in engagement with the notch in the segment 78 as shown in Fig. 11 but permitting the dog to yield rearwardly with the segment when the painting machine to which the segment is attached moves rearwardly, due to sudden or uneven pulling of the draw bar, the spring 84^b however permitting the dog to be retracted and thereby disengaged from the segment when the releasing grip 82 is operated for that purpose, incident to a change in the angular setting of the painting machine relatively to the draw bar and thus alter the course to be steered along the highway by the painting machine.

In some instances it is desirable or necessary to cover the traffic guiding line with sand immediately after such line has been painted on the highway, the sand covering thus applied preventing tracking of the paint from the freshly painted traffic line onto other portions of the highway. For this purpose, a sand-containing receptacle 94, preferably in the form of a hopper 30 to contain a suitable quantity of sand, is provided, it being supported on wheels 95 which are preferably provided with pneumatic tires to absorb shocks due to unevenness in the road surface, these wheels being preferably fixed to an axle 96 which extends rotatably through the lower portion of the receptacle 94 and is provided with agitating arms 97 which project therefrom, so that rotation of the shaft 96 caused by the rolling of the supporting wheels 95 on the highway pavement will cause agitation of the sand in the receptacle and thereby insure uniform flow of the same to the discharge opening 98 formed in the bottom thereof. In order to regulate the amount of sand discharged upon the painted line, a controlling valve 99 is mounted to slide across the discharge opening 98 so as to cover it more or less and thus determine the size of this opening, and the controlling slide may be provided with a rack bar 100 with which a pinion 101 meshes, the pinion being supported on the hopper or receptacle 94 by a bearing bracket 102 and being connected by a universal joint 103 to an operating shaft 104, the latter having a handle 105 at its upper end for rotating it. The sanding device is provided with means for attaching it to the painting machine so that it will trail in the rear thereof and the sand will be deposited therefrom onto the traffic line painted on the highway. For this purpose, the sanding device is provided with a yoke 106 which is attached to the sides of the sand receptacle or hopper 94 and has its forward portion pivotally connected by the vertical pivot pin or bolt 107 to a bar 37^a which in turn is pivotally connected by horizontal pivot screws 37^b to the rear cross member 37 of the painting machine, the pivot screws 37^b being for example rotatably fitted in down-turned ends of the bar 37^a and removably threaded in plugs secured in the ends of the rear cross member 37 which may be tubular as shown. The vertical pivot 107 is located midway of the width of the painting machine and sanding device and the vertical axis of the pivot 107 and the horizontal axis of the screws 37^b are located between the axes 75

of the pair of supporting wheels of the painting machine and the pair of supporting wheels of the sanding device so that the sanding device will trail behind the painting machine with its sand discharge opening 98 above the traffic line painted on the highway surface by the painting machine and the painting machine and sanding device may independently move vertically and thus accommodate any unevenness in the highway surface. The sanding device may conveniently 5 occupy a position beneath the attendant's seat 86 so that it will not interfere with the attendant's control of the painting machine and the sanding device will be in a position where it may be controlled by the attendant occupying said seat. 10

The operation of a highway marker constructed as hereinbefore described is generally as follows:—

Assuming the painting machine, and also the sanding device when such is used, to be attached to the laterally extending bar 64 on the inner or left hand side of the truck or vehicle, the latter is driven along the highway or the portion thereof to be painted with the traffic guiding line, 20 so that the front right wheel of the vehicle is immediately adjacent to the right hand edge of the pavement of the highway, this being accomplished by the attendant occupying the auxiliary seat 6 and manipulating the auxiliary steering wheel 5. Paint from the tanks 12 is supplied to the paint gun 48 through the flexible hose 20 and compressed air is supplied to the paint gun through the flexible hose 21. Assuming the disks 31 to be set at the proper distance apart by adjustment of 25 the roller carrying posts 39, according to the width of the traffic guiding line being painted on the highway, the paint gun is operated to spray the paint onto that portion of the highway surface which is exposed between the lower peripheral edges of the disk 31 which are held in contact with the highway surface individually by the springs 32. The paint thus spread onto the highway surface will cover the area thereof exposed between the disks but the disks in contact with the highway surface at opposite sides of the paint gun will intercept any paint spreading beyond the exposed width of the highway surface, these disks thus defining sharply the edges of the painted strip and determining the width thereof 30 in accordance with the setting or lateral spacing of the disks 31. Since these disks are in rolling contact with the highway surface, they will revolve as the painting machine is drawn forwardly, and surplus paint adhering to the inner sides of the disks will be scraped therefrom by the branches of the trough 42 and such paint will be collected in the bucket or receptacle 41, splashing or picking up of surplus paint and spreading or dropping thereof upon the highway beyond the side edges of the painted lines thereon being thereby avoided.

When the traffic line is being painted on a straight portion of a highway, the draft bar 65 is set in its central position with respect to the locking segment 78, the supporting wheels 27 of the painting machine then steering the latter in a course parallel to that of the truck or vehicle, and the setting of the slide 66 at the proper position along the bar 64 will cause the painting machine to travel along the highway centrally of the width thereof. When a traffic line is to be painted on a curve in the highway, the draft bar 65 is swung toward or from the vehicle to the proper angle according to the direction of the curve and the degree or radius thereof, the consequent set-

ting of the pivot 16 toward or from the vehicle compensating for the curve in the highway so that the traffic guiding line painted thereon by the painting machine will be located centrally of the width thereof.

When the sanding device is employed, it trails behind the painting machine and deposits a strip of sand upon the freshly painted line and thus avoids tracking of the paint therefrom until it has dried.

I claim as my invention:

1. A highway marker comprising a vehicle having front and rear wheels and means for steering it by its front wheels to travel along a highway, a wheeled painting machine adapted to travel along the highway and having means for painting a traffic guiding line on the surface thereof, means for connecting the painting machine to said vehicle to be drawn thereby, and means for steering the painting machine to travel 20 in different horizontally angular relations to the vehicle, said connecting means being located at a side of the vehicle at a point in alignment with the rear wheels thereof.

2. A highway marker comprising a vehicle having means for steering it to travel along a highway, a wheeled painting machine adapted to travel along the highway and having means for painting a traffic guiding line on the surface thereof, and draft means for connecting the 30 painting machine to said vehicle to be drawn thereby, said draft means embodying a draft bar, and means for connecting the painting machine thereto in different horizontally angular relations.

3. A highway marker for attachment to a vehicle to be drawn thereby comprising a wheeled painting machine adapted to ride on the surface of a highway and having means for painting a traffic guiding line thereon, a draft bar having means for attaching it to a side of the vehicle and 40 pivotally connected to the painting machine on a vertical axis to permit the painting machine to occupy different horizontally angular relations therewith, and means for holding the painting machine in one or another of such angular 45 relations with the draft bar.

4. A highway marker for attachment to a vehicle to be drawn thereby comprising a wheeled painting machine adapted to ride on the surface of a highway and having means for painting a traffic guiding line thereon, a draft bar having means for attaching it to a side of the vehicle and pivotally connected to the painting machine on a vertical axis to permit the painting machine to occupy different horizontally angular relations 55 therewith, and a locking segment concentric with such vertical axis and a cooperative locking dog interposed between the draft bar and painting machine for holding the latter in one or another of such angular relations with the draft bar.

5. A highway marker for attachment to a vehicle to be drawn thereby comprising a wheeled painting machine adapted to ride on the surface of the highway and having means for painting a traffic guiding line thereon, a bracket having 65 means for attaching it to the vehicle and carrying a bar to project laterally from a side thereof, a draft bar connected to the painting machine, and means for connecting the draft bar to said laterally projecting bar to draw the painting machine thereby, said connecting means comprising a slide adjustable laterally to occupy different 70 positions along said laterally projecting bar, and having a circular hub portion the axis of which is disposed horizontally, a member mounted to 75

- rock on a horizontal axis on said hub portion of the slide, and a vertical pivot connecting said rockable member to the draft bar.
6. In a highway marker for attachment to a vehicle to be drawn thereby, a bracket having means for attaching it to a side of the vehicle, a draft bar pivoted to said bracket on a vertical axis, a wheeled painting machine adapted to ride on the surface of the highway and having means for painting a traffic guiding line thereon, a yieldable draft connection between said painting machine and draft bar, said yieldable connection pivotally connecting the draft bar to the painting machine to permit the latter to occupy different horizontal angular relations with said bar, and locking means between said painting machine and draft bar for holding the painting machine in a given angular relation with said draft bar and embodying means to compensate for a yield of said draft connection.
7. A highway marker comprising a painting machine having supporting wheels adapted to ride on the surface of a highway and having means for painting a traffic guiding line thereon, a sanding device also having supporting wheels adapted to ride on the surface of the highway and having means for depositing sand upon the line painted thereon by the painting machine, and means pivotally connecting said painting machine and sanding device on a vertical axis located between the axes of the supporting wheels thereof in a position to cause the sanding device to track the painting machine.
8. In a highway marker, a painting machine comprising a frame having supporting wheels to ride on the surface of a highway, paint confining disks located between said supporting wheels to roll on the surface of the highway to be marked, parallel vertical guides slidably supporting said disks to individually move vertically relatively to said frame, and means between said frame and disks for yieldingly holding the peripheries of the disks in contact with the surface of the highway.
9. In a highway marker, a painting machine comprising a frame having supporting wheels to ride on the surface of a highway, paint confining disks individually rotatably mounted between said supporting wheels to roll on the surface of the highway to be marked and individually movable vertically relatively to said frame, and means between said frame and each of said disks for yieldingly holding the peripheries of the disks individually in contact with the surface of the highway.
10. In a highway marker, a painting machine adapted to travel on the surface of a highway, paint confining disks spaced laterally of the machine and adapted to roll on the surface of the highway, a paint gun between said disks for spraying paint onto the portion of the surface of the highway which extends between the contacting peripheries of the disks, and means for adjusting the paint gun vertically to vary its elevation above the surface of the highway.
11. A highway marker comprising a vehicle adapted to travel along a highway and a painting machine having means for connecting it to a side thereof to be drawn thereby and to travel along the highway and for adjusting it laterally of said vehicle and having means for painting a traffic guiding line on the surface of the highway, a seat for an attendant, and links, one having means for supporting it on said vehicle and another having means for supporting said seat thereon, said links being connected to one another by vertical pivots and supporting said seat adjacent to the painting machine to move laterally of the vehicle to conform with lateral adjustments of the painting machine.
12. In a highway marker comprising a motor vehicle having rear wheels and front guiding wheels for directing it along a highway and a painting machine drawn by said vehicle for painting a traffic guiding line on the surface of the highway, an auxiliary steering gear for the front guiding wheels of said vehicle located at the right hand side thereof and having manual controlling means located substantially in alignment between the right hand front and rear wheels and in a position from which the right hand front guiding wheel and the right hand edge of the highway are visible.
13. In a highway marker comprising a motor vehicle having right hand and left hand guiding wheels for directing it along a highway and fenders normally shielding said wheels, and a painting machine drawn by said vehicle for painting a traffic guiding line on the surface of the highway, an auxiliary steering gear for the right hand side thereof and controllable from a position from which the right hand edge of the highway is visible, the fender for the right hand guiding wheel of said vehicle being hinged to swing out of its normal position to expose the right hand guiding wheel and its relation to the right hand edge of the highway.
